WELL CUTTING SAMPLER

Filed Nov. 18, 1929

UNITED STATES PATENT OFFICE

OSCAR HATCHER AND EARL L. BYERS, OF TULSA, OKLAHOMA, ASSIGNORS TO GYPSY OIL COMPANY, OF TULSA, OKLAHOMA, A CORPORATION OF OKLAHOMA

WELL CUTTING SAMPLER

Application filed November 18, 1929. Serial No. 408,054.

This invention relates to a device or apparatus for obtaining samples of cuttings carried in mud-laden fluids used in rotary well drilling.

5 Where mud-laden fluid is used in the drilling of wells, such fluid, after passing from the bottom of the well to the surface of the ground, flows to the slush pit through a trough. Heretofore, in order to obtain samples of the cuttings carried in such mud-laden fluid, a box has been attached to the side of the trough and as the stream of mud-laden fluid flows through the trough and over the box, the heavy cuttings settle in the box from 10 which they can subsequently be removed from time to time and sacked and saved for examination. Such an arrangement for obtaining samples of the cuttings has several disadvantages. For instance, the box being made 15 of wood, is easily damaged and, in the arrangement generally used, the box is in a relatively inaccessible position. Again, it is difficult to remove the sample from the box and a slight error on the part of the roustabout 20 may result in a loss of the sample. Furthermore, if the box is not thoroughly cleansed after the removal of each sample, the next succeeding sample may be contaminated with 25 the cuttings of the preceding sample.

30 In view of the foregoing, the present invention contemplates a sample device that can be placed close to the well where it can be readily inspected and used. In the present sampler, means are also provided for readily 35 removing cuttings from the sampler and for flushing the sampler after the removal of each sample, so that one sample cannot be affected in any way by a preceding sample.

With these and other objects in view, the invention consists in certain details of construction and combinations and arrangements of parts all as will hereinafter be more fully described and the novel features thereof particularly pointed out in the appended claims.

45 In the accompanying drawings,— Figure 1 is a perspective view showing the arrangement of the sampler in connection with the well casing, derrick floor and trough leading to the slush pit;

50 Fig. 2 is a longitudinal sectional view of

the casing constituting a sampler or trap in which the sample of cuttings is accumulated; and

Fig. 3 is an end view of the sampler casing.

55

Referring to Fig. 1, reference numeral 10 indicates the usual well casing extending from above the derrick floor 11 down into the well hole 12. At a suitable point there is connected with the well casing 10 a slush pipe 13 through which mud-laden fluid is conducted from said casing to the slush trough 14, leading to the slush pit (not shown).

Disposed at an angle of substantially 45° to the slush pipe 13 is the sampler casing 15, said sampler being connected to pipe 13 by a nipple 16 at a point that will render the sampler readily accessible for the purpose of removing the sample of cuttings therefrom. Interposed between said nipple and casing there is a gate valve 17, whereby flow of a portion of mud-laden fluid from a main conduit or slush pipe 13 into the casing may be cut off whenever desired, as, for instance, when a sample of cuts is to be removed from the casing. As shown more particularly in Fig. 2, the casing is of rather large cross section compared to the cross section of nipple 16 and the end of said casing opposite that to which nipple 16 is attached is without an integral end wall, although it is adapted to be closed by a closure plate 18 secured on the end of the casing by wing nuts 19. As shown more particularly in Figs. 2 and 3, this closure 19 consists of a metal plate lined with a leather washer 20, the plate being pivoted on the bolt 21 for one of the wing nuts 19, while the handle portion 22 of the plate has a recess 23 therein for receiving the bolt 24 for the other wing nut 19.

Projecting at an angle of approximately 45° from the side of casing 15 and adjacent the closed end of the sampler there is a threaded outlet pipe 25 which communicates by piping 26 with the slush trough 14. Projecting at an angle of 45° from the other end of the casing and extending into the interior of said casing is a water clean-out jet 27 which is adapted to project above the der-

95

rick floor to a suitable source of water supply, the water supply to the interior of the casing through said pipe 28 and jet 27 being controlled by a valve 29 in pipe 28.

5 With this arrangement, valve 29 being closed and valve 17 being opened, a portion of the mud-laden fluid flowing through the main conduit or slush pipe 13 is diverted through nipple 16 into the sample casing or 10 trap in which the heavier cuttings will settle and accumulate while the mud-laden fluid escapes through the outlet 25 from whence it is conducted by pipe 26 to the slush trough 14. When it is desired to remove a sample 15 of cuttings from the casing 15 valve 17 is closed and the end plate or closure 18 removed by loosening the wing nut on bolt 23 and turning the plate on bolt 21. After the removal of the sample from said casing, the 20 latter may be flushed and cleansed by opening valve 29. After cleaning, valve 29 is closed, end plate 18 is restored to its closed position, and valve 17 is again opened to permit the accumulation of another sample in 25 the casing. From this it will be seen that the sample is readily obtained or removed from the casing 15, due to the accessibility of said casing and as the sample cuttings can be removed from the casing directly into 30 the sack into which they are to be stored, there is little likelihood of the sample being lost. Furthermore, the sampler casing can be easily and quickly cleansed by the stream of flushing water through jet 27 so that there 35 is no danger of any sample being contaminated by the cuttings of a previously taken sample.

What we claim is:

1. In apparatus for obtaining samples of 40 cuttings in mud-laden fluids used in rotary well drilling, the combination of a main conduit for the fluid, a casing forming a trap, said casing having an unrestricted opening at one end, a removable closure for said opening, connections for delivering flushing fluid to the casing, and a branch pipe connecting said conduit and casing.

2. In apparatus for obtaining samples of 45 cuttings in mud-laden fluids used in rotary well drilling, the combination of a main conduit for the fluid, a casing forming a trap for accumulating the cuttings, a branch pipe connecting said conduit and casing, the casing being attached to and suspended from 55 the conduit by said branch pipe, and an outlet pipe for said casing.

3. In apparatus for obtaining samples of 60 cuttings in mud-laden fluids used in rotary well drilling, the combination of a main conduit for the fluid, an elongated casing forming a trap inclined with respect to said conduit, a branch pipe connecting said conduit with the higher end of said casing, the lower 65 end of the casing being open, a removable closure for said lower open end, an outlet adja-

cent said lower end, and a connection for flushing fluid communicating with the higher end of said casing.

4. An apparatus for obtaining samples of 70 cuttings in mud-laden fluids used in rotary well drilling, the combination of a main conduit for the fluid, an elongated casing forming a trap inclined with respect to said conduit, a branch pipe connecting said conduit with the higher end of said casing, the lower 75 end of the casing being open, a removable closure for said lower open end, a cut-off valve in said branch pipe, an outlet in the upper surface of the casing adjacent said lower end, and a connection for a flushing fluid 80 communicating with the upper surface of said casing adjacent the higher end thereof.

5. An apparatus for obtaining samples of 85 cuttings in mud-laden fluids used in rotary well drilling, comprising a conduit for the fluid connected to the outlet from the well casing and having an opening in its under side, a tubular member attached to said conduit about its opening and extending downwardly therefrom, and a closure on the lower 90 end of said tubular member.

6. An apparatus for obtaining samples of 95 cuttings in mud-laden fluids used in rotary well drilling, comprising an inclined conduit for the fluid connected at its upper end to the outlet from the well casing and having an opening in its under side, a tubular member attached to said conduit about its opening and extending in the same general direction as the conduit, but downwardly therefrom, 100 and a closure on the lower end of said tubular member.

7. An apparatus for obtaining samples of 105 cuttings in mud-laden fluids used in rotary well drilling, comprising an inclined conduit 110 for the fluid connected at its upper end to the outlet from the well casing and having an opening in its under side, a tubular member attached to said conduit about its opening and extending in the same general direction as the conduit, but downwardly therefrom, a removable closure on the lower end of said tubular member, and means adjacent the conduit for cutting off flow of said fluid into 115 said tubular member.

8. An apparatus for obtaining samples of 120 cuttings in mud-laden fluids used in rotary well drilling, comprising a conduit for the fluid connected to the outlet from the well casing and having an opening in its under side, a tubular member attached to said casing about its opening and extending downwardly therefrom, a removable closure on the lower end of said tubular member, a valve in the upper portion of said tubular member for cutting off flow of mud-laden fluid into said tubular member, and means for injecting 125 flushing fluid into said tubular member.

9. An apparatus for obtaining samples of 130 cuttings in mud-laden fluids used in rotary

well drilling, comprising an inclined conduit for the fluid connected at its upper end to the outlet from the well casing and having an opening in its under side, a tubular member attached to said conduit about its opening and extending in the same general direction as the main line of flow but downwardly therefrom, a removable closure on the lower end of said tubular member, a valve in the upper portion of said tubular member for cutting off flow of mud-laden fluid into said tubular member, and means for injecting flushing fluid into said tubular member.
